UNITED STATES PATENT OFFICE.

THADDEUS F. BAILY, OF ALLIANCE, OHIO.

SOAKING PIT.

Application filed March 18, 1924. Serial No. 700,003.

To all whom it may concern:

Be it known that I, THADDEUS F. BAILY, a citizen of the United States, residing at Alliance, in the county of Stark and State of Ohio, have invented certain new and useful Improvements in Soaking Pits, of which the following is a specification.

This invention relates to soaking pits and has for its objects to provide a gas tight soaking pit, in which hollow partition walls divide the pit into a plurality of holes, heating means such as electric resistance elements being located through the hollow partition walls to heat the ingots in a non-oxidizing atmosphere.

The above and other objects may be attained by constructing the soaking pit in the manner illustrated in the accompanying drawing, in which—

20 Figure 1 is a longitudinal, sectional view through a soaking pit embodying the invention;

Fig. 2, a section on the line 2—2, Fig. 1; and

25 Fig. 3, a transverse section through a partition wall of slightly modified construction.

Similar numerals refer to similar parts throughout the drawing.

The pit may comprise a rectangular foundation 1 of refractory material built below the level of the floor 2 and divided into a plurality of holes 3 as by partition walls 4, which are preferably formed of carbide of silicon or similar material. End walls 5 of 35 the same construction as the partition walls 4, are provided in each end of the pit, forming the outer side walls of the end holes.

Each of these partitions and side walls of the holes is hollow, preferably having two 40 longitudinal passages 6 adapted to contain heating means such as an electric heating element comprising the granular carbonaceous material 7, into each end of which is inserted an electrode 8 connected to an electric circuit, whereby the current passing 45 through the carbonaceous material from one electrode to the other, heats the same to the desired temperature.

The upper and lower heating elements in 50 each wall thus provide for heating the upper and lower portions of the hole uniformly and are separated by a horizontal partition 9 also formed of carbide of silicon or other material, which will not reduce in the presence of carbon.

The bottom 10 of each hole is also formed

of a material which will not reduce in the presence of carbon and the usual clean-out aperture 11 is provided therein.

A sand trough 12 is preferably provided 60 around the upper edge of each hole to receive the depending flange 13 formed around the edge of each cover 14, which is preferably formed of fire brick with a steel or iron covering, a ring 15 being provided therein 65 for removing the cover.

In Fig. 3 is shown a modified form of partition or side wall for each hole. In this construction, the upper and lower hollow or tubular containers for the resistance elements are indicated at 16 and 17 respectively and are spaced by means of a horizontal partition 18 of suitable refractory material, said partition extending outward upon each side of the wall as indicated at 19 in order 75 to support the ingots away from the resistance elements.

In charging the soaking pit, the cover is removed from the hole to be charged and the ingots shown at 20 are charged through the 80 open top of the hole, being placed in upright position as shown in the drawing. Coke breeze or other granular carbon is placed in the bottom of the hole to provide a non-oxidizing atmosphere.

After the hole is charged the cover is placed thereon, the sand seal providing a gas tight hole in which the ingots are soaked, and the heating elements being located through the hollow side walls of the 90 holes are thus kept out of the furnace atmosphere.

From the above, it will be seen that by constructing the soaking pit in the manner illustrated, no additional space is required 95 for accommodating the heating elements as they are located through the partition walls and side walls of the holes, which walls are necessary in the ordinary construction.

It will also be seen that the ingots are 100 soaked in a non-oxidizing atmosphere, since each hole is made gas tight and it cut off from the heating elements by the partition walls.

Further, the non-oxidizing atmosphere is 105 maintained in each hole by placing coke breeze or the like upon the bottom of the hole.

I claim:—

1. A soaking pit having a plurality of 110 holes lined with carbide of silicon or other material which will not reduce in the pres-

- ence of carbon and electric heating elements located through the side walls of the holes.
2. A soaking pit having a plurality of holes and a plurality of heating elements located through the side walls of the holes, one of said elements being arranged to deliver heat at the upper part of each hole and another element being arranged to deliver heat at the lower part of the hole.
3. A soaking pit having a substantially hollow partition wall containing a resistance element such as broken carbon, the outer face of the wall forming the side wall of the pit.
4. A soaking pit having side walls formed of carbide of silicon or other material which will not reduce in the presence of carbon and electric heating elements located within said side walls.
5. A soaking pit having side walls formed of carbide of silicon or other material which will not reduce in the presence of carbon and heating elements located within said side walls.
6. In a furnace for heating ingots in a vertical position, a bottom to support the ingots, an opening in the top of the furnace for charging the ingots, carbide of silicon walls forming the sides of the furnace and electric heating elements placed in said walls for supplying heat.
7. In a furnace for heating ingots in a vertical position, a bottom to support said ingots, an opening in the top of the furnace for charging the ingots, carbide of silicon partition walls dividing the furnace into a plurality of compartments and electric heating elements placed in the partition walls for supplying heat.
8. In a furnace for heating ingots in a vertical position, a bottom to support said ingots, an opening in the top of the furnace for charging the ingots, carbide of silicon partition walls dividing the furnace into a plurality of compartments, and enclosed carbonaceous resistance elements located in the partition walls.
9. In a furnace for heating ingots in a vertical position, a bottom to support said ingots, an opening in the top of the furnace for charging the ingots, carbide of silicon partition walls dividing the furnace into a plurality of compartments, and a plurality of resistance elements in each partition wall.
10. In a furnace for heating ingots in a vertical position, a bottom to support said ingots, an opening in the top of the furnace for charging the ingots, partition walls dividing the furnace into a plurality of compartments, upper and lower resistance elements located in each partition wall and a horizontal partition of refractory material located between the upper and lower resistance elements.
11. In a furnace for heating ingots in a vertical position, a bottom to support said ingots, an opening in the top of the furnace for charging the ingots, partition walls dividing the furnace into a plurality of compartments, said partition wall being of low electrical conductivity and electric heating elements located therein.
12. A closed furnace of the character described provided with enclosed carbonaceous electric heating elements and having a loose carbonaceous material such as coke breeze upon the bottom to provide a non-oxidizing atmosphere.
13. A closed type gas tight furnace having an opening in the top, a sand sealed cover fitted over said opening, and electric heating elements enclosed in the walls of the furnace.
14. A closed type gas tight furnace having an opening in the top, a sand sealed cover fitted over said opening, and electric heating elements enclosed in the side walls of the furnace.
15. A closed type gas tight furnace having an opening in the top, a sand sealed cover fitted over said opening, and electric heating elements enclosed in the walls of the furnace, and loose, granular carbon on the bottom of the furnace to provide non-oxidizing atmosphere.
16. A closed type gas tight furnace having an opening in the top, a sand sealed cover fitted over said opening, electric heating elements enclosed in the side walls of the furnace, and loose, granular carbon on the bottom of the furnace to provide non-oxidizing atmosphere.
17. A soaking pit divided into a plurality of gas tight holes by means of partition walls, electric heating elements enclosed in said walls and a sand sealed cover enclosing the top of each hole.
18. A closed furnace of the character described provided with carbonaceous electric heating elements and having a loose carbonaceous material such as coke breeze upon the bottom to provide a non-oxidizing atmosphere.
19. A closed type furnace of the character described provided with electric resistance heating means and having a loose carbonaceous material such as coke breeze upon the bottom to provide a non-oxidizing atmosphere.
20. A soaking pit for heating ingots in a vertical position having electric resistance elements located in the side-walls and refractory ribs upon the side walls for supporting the ingots out of contact with the resistance elements.
21. A soaking pit having a gas-tight cover and gas tight walls provided with spaced upper and lower openings therein and heating means within said openings.
22. A soaking pit having a gas-tight

cover and gas tight walls, provided with spaced upper and lower openings, thermal and electric resistance elements within said openings.

5 23. A closed type gas tight furnace including heating means exterior to the walls of the heating chamber and a loose car-

bonaceous material upon the bottom of the heating chamber to support ingots to be heated and to insure a reducing atmosphere in the furnace chamber.

In testimony that I claim the above, I have hereunto subscribed my name,

THADDEUS F. BAILEY.
